UNITED STATES PATENT OFFICE

95,961

DESIGN FOR A RADIOCABINET

Nathan George Horwitt, New York, N. Y.

Application May 26, 1934, Serial No. 51,934

Term of patent 3½ years

To all whom it may concern:

Be it known that I, Nathan George Horwitt, a citizen of the United States, residing in the city of New York, in the county of Queens and State of New York, have invented a new, original, and ornamental Design for a Radio Cabinet, of which the following is a specification, reference being had to the accompanying drawing, forming a part hereof.

Figure 1 is a perspective view from the left front of a radio cabinet, showing my new design,

Figure 2 is a perspective view from the left rear of the same cabinet, showing my new design.

I claim:

The ornamental design for a radio cabinet, as shown.

NATHAN GEORGE HORWITT.
